UNITED STATES PATENT OFFICE.

ALBERT A. HUSEBY, OF CHICAGO, ILLINOIS.

MOTOR-CONTROLLING MECHANISM FOR TALKING-MACHINES.

1,240,455.

Specification of Letters Patent. Patented Sept. 18, 1917.

Application filed April 6, 1917. Serial No. 160,150.

To all whom it may concern:

Be it known that I, ALBERT A. HUSEBY, a citizen of the United States, residing at Chicago, in the county of Cook and State 5 of Illinois, have invented certain new and useful Improvements in Motor-Controlling Mechanisms for Talking-Machines, of which the following is a specification.

This invention relates to motor-control- 10 ling mechanisms more especially designed for talking machines, and has reference more particularly to automatic devices for effecting the application and release of the brake through the agency of a movable element of 15 the machine,—usually the swinging tone-arm. Recent developments in this art have produced a number of devices wherein a spring-actuated brake is normally held re- 20 tracted by a latch mechanism, and this lat- 25 ter is unlatched by a latch-tripping me- 30 chanism located in the path of movement of the tone-arm and engaged by the latter at the limit of its inward movement in playing a record. Some of these devices are also pro- 35 vided with a brake-retracting and latch re- 40 setting device that is struck by the tone-arm when the latter is returned to its starting 45 position.

My present improvements relate to auto- 50 matic stopping and starting devices of this general character, and the general purpose and aim of the invention is to produce an automatic motor-controlling mechanism that shall be simple and economical to manufac- 55 ture, easy to manipulate, and efficient, sensi- 60 tive and reliable in operation. This and other objects and advantages of the invention will be apparent to those skilled in the art from a consideration of the following 65 detailed description, taken in connection with the accompanying drawings, which show a practical and approved embodiment of the 70 invention, and in which—

Figure 1 is a bottom plan view of the 75 mechanism shown as applied to the under- 80 side of the usual metal plate in which the turntable is mounted and from which the motor and its adjuncts are suspended;

Fig. 2 is a top plan view of the mecha- 85 nism shown in Fig. 1 turned end for end and with the attaching plate of the frame structure cut off to disclose underlying parts;

Fig. 3 is a side elevation as viewed from the right of Fig. 1 inverted;

Fig. 4 is an end elevation as seen from the left of Fig. 3;

Figs. 5 and 6 are enlarged detail sections on the corresponding lines of Fig. 3, the stationary frame parts appearing in dotted lines for the sake of clearness;

Fig. 7 is an enlarged vertical section on the line 7—7 of Fig. 2.

Referring to the drawings, 10 designates the usual metal plate of a cabinet talking machine in which the turntable is mounted and to the underside of which the motor and its associated parts are secured. As here shown said plate has a rear extension 10' in which is formed an elongated opening 11 that accommodates the swinging move- 15 ment of the upright portion of the tone-arm indicated in Fig. 1 at 12.

To the under side of the plate 10 is se- 20 cured a frame structure which supports the several elements of the mechanism, said 25 frame structure comprising an attaching plate 13, a pair of parallel depending L- 30 shaped arms 14, and a bracket arm 15 ex- 35 tends horizontally from one of the arms 14. In and between the arms 14, at the 40 elbows thereof is journaled a rock shaft 16, on one overhanging end of which is a disk 17 (Fig. 4) carrying an eccentric pin 18 that is engaged by the slotted end 19 of a 45 brake-lever 20, said brake-lever being ful- 50 crumed at 21 and carrying at its other end a brake-block 22 that co-operates with the 55 periphery of a brake-disk 23 on the governor shaft of the motor. Fast on the rock shaft 60 is an arm 24 to the free end of which is 65 connected a tensile spring 25 anchored at 26, 70 said spring, through the described connec- 75 tions, normally tending to apply the brake- 80 block 22 to the disk 23.

Keyed to the other overhanging end of 85 the rock shaft 16 is a ratchet disk 27, on the inner face of which is formed a single 90 tooth or shoulder 28 (Figs. 5 and 6). Piv- 95 oted on the lower side of the horizontal limb of one of the side frame members 14 is a 100 detent pawl 29, the nose of which is con- 105 stantly urged against the inner face of the ratchet disk 27 by a spring 30. By refer- 110 ence to Fig. 5 it will be seen that the tooth 28 has a long gradually inclined side 28', over which the nose of the pawl wipes as the disk is turned in a clockwise direction, viewing Fig. 5, by the brake-retracting mechanism next to be described, until the nose of the pawl snaps over the square end 110 or shoulder 28, thus locking the disk against turning in the reverse direction under the

pull of spring 25 until the pawl has been retracted.

On the outer end of bracket arm 15 is pivoted at its elbow a bell-crank lever, one arm 31 of which extends across the path of travel of the tone arm 12, as shown in Fig. 1, and the other arm 32 of which has a bent end engaging behind the arm 24 of the rock shaft, as best shown in Fig. 3. From this it will be seen that as the tone-arm is swung outwardly of the record to starting position, it strikes the arm 31 of the bell-crank lever and rocks the shaft 16, against the pull of spring 25, withdrawing the brake 22 and 10 at the same time carrying the ratchet tooth 28 into locking engagement with the detent pawl 29. This position of the parts is maintained during the playing of the record; and when the tone-arm reaches the end of 15 the record it strikes a pawl-tripping device 20 next to be described, by which the pawl 29 is retracted and the spring 25 allowed to set the brake.

33 designates a rod extending between the 25 horizontal limbs of the side frame members 14, and forming with the rock shaft 16 a slideway upon which is mounted a slide 34. From one end of this slide extends a buffer arm 35 carrying at its free end a buffer block 36 of felt or like material. 37 designates a push-rod disposed parallel with the rod 33, and having a reduced end 37' which is slidably mounted in one of the arms 14, this reduced end being adapted to strike an 35 upstanding tail-piece 29' of the pawl 29, as best shown in Figs. 5 and 6, to withdraw the pawl from the ratchet. The other end of the push-rod is made tubular for a short distance so as to slidably engage an adjustable mandrel 38 (Fig. 3) carried by the other arm 14. The slide 34 extends over the 40 push-rod 37, as shown in Fig. 7, but has no engagement therewith, and is formed with a slot 39 through which project a pair of spaced hinge-lugs or ears 40 on the inner end of a trip-arm 41, said lugs being slidably along the push rod when pushed by the slide 34. The trip arm 41 has a downwardly bent free end 42 that lies in front of the 45 buffer block 36. A light spring 43 (Figs. 1 and 7) acts on the hinge-lugs of the trip arm in such a manner as to normally maintain the depending end 42 of the trip arm spaced slightly away from the buffer block 36.

The slide 34 is set to the desired position on the slideway by a manually operated lever 44 (Fig. 1) and a link connection 45 therefrom to a stud on the lower side of the 50 slide 34. This manually operated slide setting mechanism is identical with that shown and described in my former Patent No. 1,224,547, dated May 1, 1917, to which reference may be had for a full disclosure.

In the operation, the tone arm is set with

the needle or stylus at the inner end of the record groove. The slide 34 is then manually moved inward until the free end 42 of the trip arm and the buffer block 36 strike the tone arm. The tone arm is then swung outwardly, retracting the brake and setting the detent mechanism, as already described. As the tone arm moves away from the buffer block, the spring 43 acts to set the free end 42 of the trip arm slightly away from the buffer block. When now the tone arm, at the completion of the playing of the record, strikes the end 42 of the trip arm the hinge lugs or ears 40 of the latter bite on and actuate the push rod, thus releasing the detent mechanism and allowing the spring 25 to set the brake and stop the motor.

Without limiting myself to the specific details shown and described,—

I claim:

1. In a motor-controlling mechanism for talking machines, the combination of a brake, brake applying and releasing mechanism including a rock shaft and a spring tending to apply said brake through said shaft, a ratchet disk connected to said shaft, a detent pawl, a spring urging said pawl into engagement with said disk, a push-rod for disengaging said pawl from said disk, and a push-rod actuating member located in the path of a movable element of the machine.

2. In a motor-controlling mechanism for talking machines, the combination of a brake, brake-applying and releasing mechanism including a rock shaft and a spring tending to apply said brake through said shaft, a ratchet disk connected to said shaft, a detent pawl, a spring urging said pawl into engagement with said disk, a push-rod for disengaging said pawl from said disk, a push-rod actuating member operated by a movable element of the machine when moving in one direction, and a brake-retracting member actuated by said movable element when moving in the opposite direction.

3. In a motor-controlling mechanism for talking machines, the combination of a brake, brake-applying and releasing mechanism including a rock shaft and a spring tending to apply said brake through said shaft, a ratchet disk connected to said shaft, a detent pawl, a spring urging said pawl into engagement with said disk, a push-rod for disengaging said pawl from said disk, and a trip-arm slidably mounted at one end on said push-rod so as to be adjustable lengthwise of the latter and having its free end disposed in the path of a movable element of the machine.

4. In a motor-controlling mechanism for talking machines, the combination of a brake, brake applying and releasing mechanism including a rock shaft and a spring tending to apply said brake through said

- shaft, a ratchet disk connected to said shaft, a detent pawl, a spring urging said pawl into engagement with said disk, a push-rod for disengaging said pawl from said disk,
- 5 5 a trip-arm slidably mounted at one end on said push-rod so as to be adjustable lengthwise of the latter and at its free end adapted to be contacted by a movable element of the machine when moving in one direction,
- 10 10 an arm on said rock shaft to which one end of said brake-applying spring is connected, and a bell-crank lever having one arm thereof engaging said rock shaft arm and its other arm adapted to be contacted by
- 15 15 said movable element when moving in the opposite direction.

5. In a motor-controlling mechanism for talking machines, the combination of a frame structure, a rock shaft journaled in said frame structure, a brake lever at one end connected to and actuated by said rock shaft and carrying a brake-block at its other end, an arm on said shaft, a spring connected to said arm and tending to apply said brake-block, a ratchet disk fast on said shaft, a detent pawl pivoted on one of said side frame members, a spring urging said pawl into engagement with said disk, a push-rod supported by said frame structure parallel with said shaft for disengaging said pawl from said disk, and a trip-arm slidably mounted at one end on said push-rod so as to be adjustable lengthwise of the latter and having its free end disposed in the path of a movable element of

35 35 the machine.

6. In a motor-controlling mechanism for talking machines, the combination of a frame structure having parallel side members, a rock shaft journaled in and between said side members, a brake-lever at one end connected to and actuated by said rock shaft and carrying a brake-block at its other end, a spring tending to apply said brake-block, a ratchet disk fast on said shaft, a detent

45 45 pawl, a spring urging said pawl into en-

gagement with said disk, a rod connecting said side frame members parallel with said shaft and forming with the latter a slideway, a slide on said slideway having a projecting buffer arm, a buffer-block carried by the free end of said buffer-arm, a push-rod supported by and between said side frame members parallel with said slideway, and a trip-arm slidably mounted at one end on said push-rod and actuated lengthwise of the latter by said slide, said trip-arm resting upon said buffer arm and having a down turned free end lying slightly in advance of said buffer-block.

7. In a motor-controlling mechanism for talking machines, the combination of a frame structure having parallel side members, a rock shaft journaled in and between said side members, a brake lever at one end connected to and actuated by said rock shaft and carrying a brake-block at its other end, a spring tending to apply said brake-block, a ratchet disk fast on said shaft, a detent pawl pivoted on one of said side frame members, a spring urging said pawl into engagement with said disk, a rod connecting said side frame members parallel with said shaft and forming with the latter a slideway, a slide on said slideway having a rigid projecting buffer arm, a buffer-block carried by the free end of said buffer arm, a push-rod supported by and between said side frame members parallel with said slideway, a trip-arm formed at one end with a pair of separated down turned lugs slidably mounted on said push-rod and actuated lengthwise of the latter by said slide, said trip-arm resting upon said buffer arm and having a down turned end lying alongside said buffer-block, and a spring engaging said trip-arm in a manner to maintain its free end normally slightly spaced from said buffer-block.

ALBERT A. HUSEBY.
